UNITED STATES PATENT OFFICE.

ELBERT E. LOCHRIDGE, OF SPRINGFIELD, MASSACHUSETTS.

VALVE.

1,270,424.

Specification of Letters Patent. Patented June 25, 1918.

Application filed February 14, 1916. Serial No. 78,097.

To all whom it may concern:

Be it known that I, ELBERT E. LOCHRIDGE, a citizen of the United States, and a resident of Springfield, county of Hampden, 5 and Commonwealth of Massachusetts, have invented an Improvement in Valves, of which the following description, in connection with the accompanying drawings, is a specification, like characters on the drawings representing like parts.

This invention relates to valve mechanisms and more particularly to valve mechanisms for controlling the admission of flushing water to the bowls of water-closets.

15 The invention is an improvement upon the valve mechanism shown in my co-pending application, Serial No. 45,401, filed August 13, 1915.

The character of the invention may be best 20 understood by reference to the following description of an embodiment thereof illustrating the invention shown in the accompanying drawings, wherein,—

Figure 1 is a vertical section through the 25 valve mechanism shown herein as embodying the invention;

Fig. 2 is a similar sectional view of part 30 of said mechanism showing the inlet and outlet tubes therefor in different positions;

Fig. 3 is a side elevation of one type of 35 bowl having the valve mechanism connected thereto to deliver water through the lower end of its casing; and

Fig. 4 is a side elevation of another type 40 of bowl having the valve mechanism connected thereto to deliver water through the side of its casing.

Referring to the drawings, the valve mechanism shown therein as illustrating the 45 invention comprises a casing 1 having a reduced upper end portion 3 and a shoulder 5 at the base of said portion. A cylindrical wall 7 in the casing divides the same into a central chamber 9 and an annular chamber

11. The upper end of the wall 7 has a head 13 tapped therein having feet 15 projecting outward beyond said wall for engagement with the sides of said casing to hold said wall properly spaced therefrom. Said head

50 has feet 17 projecting upward therefrom for engagement with the casing shoulder 5 referred to to limit inward movement of said wall in the casing. The feet 15 and 17 are narrow and distributed to leave substantial water passages between them to permit the water to flow from the central chamber

to the outer chamber as more fully herein-after described. The lower end of the casing is provided with a head 19 threaded thereon and adapted to engage a spacing 60 ring 21 engaging the lower reduced end of said wall. Obviously when the head is tightened in place it will operate through said ring to press said wall up into said casing with its feet 17 in tight engagement with 65 the shoulder 5.

The head 19 has a neck 23 projecting downward therefrom externally threaded to receive a pipe 25. The lower end of the wall 7 has a neck 27 projecting outward therefrom and preferably registers with and has substantially the same internal diameter as the neck 23.

A neck 29 projects outward laterally from the casing and is threaded to receive 75 a pipe 31. A neck 33 projects inward from the wall 7 and preferably registers with and has substantially the same internal diameter as the neck 29.

An important feature of the invention relates to interchangeable means for admitting 80 water to the casing from the bottom thereof and discharging water from the casing through the side thereof; or for admitting water to the casing from the side thereof and discharging water from the casing through 85 the bottom thereof. To accomplish this an inlet tube 35 is provided adapted to fit in and be threaded to either of the wall necks 27 and 33, and has a smooth portion for 90 tight fit with either of the casing necks 23 and 29. This inlet tube has both of its ends open and when introduced to either of its positions presents a closed wall extending transversely across the outer chamber 11 95 and cutting off the latter from communication with said tube. As a result when water is introduced through said tube it will be conducted directly into the central chamber and not to the outer chamber.

100 An outlet tube 37 is provided having a portion for threaded engagement with either of the wall necks 27 and 33 and has a smooth portion for tight fitting engagement with either of the casing necks 23 and 29. This 105 tube has an open end, and a closed end 39 cutting off said tube from communication with the central chamber. This tube is adapted, however, to communicate with the outer or annular chamber through apertures 110 41 in the wall of said tube. When the tube 37 is in either of its positions it will, there-

fore, permit water to flow from the outer, annular chamber therethrough, but will prevent water from flowing from the central chamber outward therethrough.

5 To limit inward adjustment of the tubes each may be provided with a circumferential end shoulder 43 adapted to engage the ends of the necks 23 and 29. These shoulders are, however, sufficiently small to 10 readily fit into the pipes 25 and 31, and thus the latter conceal the tubes and make tight joints with said necks independently of said tubes. Each tube may have a series of internal notches 45 adapted to receive a special wrench to facilitate the screwing and unscrewing thereof.

Some water-closet bowls are constructed and arranged to receive flushing water through the top thereof as, for example, 20 shown in Fig. 3, whereas others are designed to receive their flushing water through an end thereof as, for example, shown in Fig. 4. The interchangeable tube construction described permits a standard valve to be 25 made which may be readily applied to either type of bowl. If the valve is to be applied to the form of bowl shown in Fig. 3, the inlet tube 35 is introduced into the side of the casing, as shown in Fig. 1, and the 30 outlet tube 37 is introduced into the bottom of the casing, as shown in Fig. 1. With the tubes thus positioned the water will be conducted from the city main to the pipe 31 and pass through the inlet tube 35 into the 35 central chamber. It will pass thence through the head of the wall 7 as controlled by a valve to be described, into a chamber in the casing above said head, and pass thence downward through the outer, annular chamber and down through the outlet 40 tube 37 into the pipe 25 which is connected to the bowl.

If the valve is to be applied to the type of bowl shown in Fig. 4, the inlet and outlet 45 tubes are changed from their positions shown in Fig. 1 to their positions shown in Fig. 2. Then the inlet tube 35 will be applied to the lower end of the casing and the outlet tube 37 will be applied to the side of the casing. When thus positioned the water 50 will be conducted from the city main into the pipe 25 and through the tube 35 up into the central chamber and will pass thence as controlled by the valve at the head of said 55 chamber downward through the annular chamber and laterally through the outlet tube 37 at the side of the casing through the pipe 31 into the bowl.

Thus by an extremely simple adjustment 60 the mechanism can be adapted for either type of bowl, thereby greatly extending the field of its usefulness and the desirability thereof.

The valve mechanism for controlling the 65 discharge from the central chamber to the

annular chamber, may be similar to that shown in my said co-pending application. This mechanism comprises a main valve 47 connected by a sleeve 49 with a piston 51 movable in the cylinder formed by the upper 70 reduced end 3 of the casing. This piston is normally cut off from communication with the central chamber by a tubular controlling valve 53, the upper end of which is adapted to engage a packing seat 55 carried by a plug 75 57 tapped in the upper end of said casing. The sleeve has internal ribs 59 tapped to receive the reduced end of a stem 61 projecting upward through a stuffing box in said plug. A handle knob 63 is threaded to the 80 upper end of said stem. The tubular valve is normally seated by a coil spring 65 encircling said stem and confined between the upper end of said plug and the lower end of said knob.

When the knob 63 is depressed water from the central chamber passes upward through the tubular valve into the cylinder above piston 51. Since the latter has a greater area subject to pressure than the valve, the 90 resulting differential pressure causes the piston to move downward and open the valve. Promptly on release of the knob 63 the tubular valve is snapped to its seat by the spring 65, thereby cutting off escape for the water 95 from the cylinder above the piston. To permit this water to gradually escape and thereby retard the return of the main valve 47 to its seat, a by-pass duct 67 is provided in the plug having one end communicating with 100 the cylinder above the piston and its opposite end communicating with an annular passage 69 between the tubular valve and a sleeve 71 thereon. The water gradually escapes from the cylinder above the piston through the 105 duct 67, passage 69 and ports 73 in said sleeves 71 and 49, into the chamber above the head 13 of the wall 7. Thus the valve is permitted to return gradually and quietly to its seat.

110 A coil spring 75 encircling the sleeve 49 is confined between the head 13 and the piston 51, and will serve to return the main valve to its seat if for any reason the supply of water in the city main should fail. 115 Under normal conditions, however, the pressure of the water will be sufficient to return the valve 47 to its seat.

Having described one illustrative embodiment of the invention without limiting the 120 same thereto, what I claim as new and desire to secure by Letters Patent is:

1. The combination with a casing of a wall therein dividing the same into chambers, and inlet and outlet tubes extending 125 across one of said chambers, one of said tubes having a closed end and an apertured side wall, and the other of said tubes having open ends and a closed side wall, said tubes being interchangeable according to the de- 130

sired direction of delivery of fluid from said casing.

5 2. The combination with a casing of a wall therein dividing the same into inner and outer chambers, and inlet and outlet tubes crossing said outer chamber and tapped to said wall, one of said tubes having communication with said inner chamber and no communication with said outer chamber, and the other of said tubes having communication with said outer chamber and no communication with said inner chamber, said tubes being interchangeable according to the desired direction of delivery of fluid from said casing.

10 3. The combination with a casing of a wall therein dividing the same into inner and outer chambers, necks projecting from said wall and casing at different points, and interchangeable inlet and outlet tubes adapted to fit in said necks, one of said tubes being formed for communication with said outer chamber but not with said inner chamber, and the other of said tubes being formed for communication with said inner chamber but not with said outer chamber.

15 4. The combination with a casing of a wall therein dividing the same into chambers, interchangeable fluid-directing tubes adapted to extend transversely across one of said chambers, one of said tubes having communication with only one of said chambers, and the other of said tubes having communication with the other chamber.

20 5. The combination with a casing of a wall therein dividing the same into inner and outer chambers, registering ports in said wall and casing at one end of the latter, registering ports in said wall and casing at the side of the latter, and interchangeable inlet and outlet tubes adapted to fit said

ports to control the direction of fluid flow to and from said casing.

25 6. The combination with a casing of a cylindrical wall therein dividing the same into central and annular chambers, said wall and casing having registering ports therein, and interchangeable inlet and outlet tubes fitting said ports, one of said tubes having an open end, a closed end, and an apertured for communication with said annular chamber, and the other of said tubes having open ends, and a closed wall for preventing communication thereof with said annular chamber.

55

30 7. The combination with a casing of a wall dividing the same into chambers, said casing and wall having registering ports therein, and inlet and outlet tubes adapted to interchangeably fit said ports to control the direction of flow of fluid to and from said casing.

60

35 8. The combination with a casing of a wall therein dividing the same into chambers, said casing and wall having ports therein and inlet and outlet tubes entered into said ports for controlling the direction of fluid flow to and from said casing.

65

40 9. The combination with a casing of a wall therein dividing the same into chambers 70 9 and 11, and interchangeable tubes 35 and 37, one to conduct fluid to one of said chambers in either of its positions, and the other to conduct fluid from the other chamber in either of its positions.

75

In testimony whereof, I have signed my name to this specification, in the presence of two subscribing witnesses.
